UNITED STATES PATENT OFFICE.

ORTON L. PRIME AND ALFRED LAUKHUFF, OF MILWAUKEE, WISCONSIN, ASSIGNEES
TO THE PRIME MFG. CO., OF MILWAUKEE, WISCONSIN.

LATCH.

Application filed December 30, 1927. Serial No. 243,556.

This invention relates to latches.

Objects of this invention are to provide a novel form of latch such, for instance, as a window latch, which is of very simple and substantial construction, which will draw the two portions of the window sash together, which will fasten itself in place against dislodgment, and which is easy to operate.

Further objects are to provide a latch which may be very simply and cheaply manufactured and which is so constructed that it can be readily changed during the course of assembly from a right to a left hand latch.

15 An embodiment of the invention is shown in the accompanying drawings in which:

Figure 1 is a plan view of the latch showing it in closed position;

Figure 2 is a sectional view on the line 20 2—2 of Figure 3 showing the latch open;

Figure 3 is a sectional view drawn to an enlarged scale on the line 3—3 of Figure 2;

Figure 4 is a sectional view on the line 4—4 of Figure 3.

25 Referring to the drawings, it will be seen that the latch comprises two base members indicated by the reference characters 1 and 2 which are adapted for attachment to the two sashes 3 and 4, respectively, as shown in Figures 1 and 2. The base member 2 is provided with a headed stud 5. Preferably, these base members are triangular and apertured in their corners for the reception of the attaching screws, as indicated. They

30 may be stamped from sheet metal and may be provided with downturned flanges, as developed in Figure 3. It is an easy matter to countersink the bases for the tapered heads of the attaching screws 6. The base member

40 1 carries a pivot pin 7 which is provided with an enlarged head and which pivotally supports a bottom washer 8 and a top washer 9. The top washer is provided with a recess 10 which surrounds the enlarged head of the

45 pin 7 and a compression spring 11 loosely surrounds the pin and bears at one end against the head of the pin and at the other end against the upper washer 9. The upper washer is provided with a pair of manipulating ears 12, as shown in Figures 1 and 4.

The washers receive between them a latching arm 13 which is provided with a hook-like end 14 adapted to engage the headed stud 5 in locked position, as shown in Figure 1.

This latching arm is provided with a curved slot 15 (see Figure 2) through which the pivot pin 7 projects.

The washers 9 and 8 are joined by means of an eccentrically mounted pin 16 (see 60 Figure 3) and such pin 16 passes through an aperture in the arm 13. Preferably, it is received in a socket or aperture formed in the washer 9, such socket being closed at its upper end. This member 9 may have a pair 65 of apertures, as indicated by the reference character 17 in Figure 4, so that the device may be readily changed during assembly to a right or left hand latch by placing the pin in one or the other of the apertures 17 and by turning the latching arm 13 over. The bottom washer 8 may be provided with a ring of apertures 17' as shown in Figures 1 and 3.

The base 1 is provided with a stop 18 (see 75 Figures 1 and 2) against which the latching arm is adapted to contact when it is swung to extreme open position. Obviously, the base 1 may be turned 120 degrees when the device is assembled for a left hand latch, to 80 properly position the stop 18.

In operating the device, the washers are turned by means of the ears or wings 12 in a counter-clockwise direction to close the latch for the form shown in the drawings. 85 The pin 16 transmits motion to the arm 13 and such arm is gripped between the spring pressed washers and rocks into contact with the headed stud 5, as shown in dotted lines in Figure 1. Continued rotation of the 90 washers causes the arm to move inwardly as the pin moves towards and past dead center and thus the hook-like end 14 is drawn into binding engagement with the stud 5. Upon releasing motion or rotation of the 95 washers in a clockwise direction, the latching arm 13 is first moved outwardly and thereafter rocked into the position shown in Figure 2.

It will be seen therefore that a very simple 100 type of latch has been provided, which may be very cheaply manufactured, which is easy to install, and which is secure in operation.

Although the invention has been described in considerable detail, such description is 105 intended as illustrative rather than limiting as the invention may be variously embodied and as the scope of such invention is to be determined as claimed.

We claim:

1. A latch comprising a pair of plates, one of said plates having a headed stud, a pair of washers pivotally supported from the other plate, a latch arm mounted between said washers and having a slot formed therein, a pivot pin carried by said last mentioned plate and passing through said washers and said latch arm, and a pin extending through said latch arm and entering said washers, said latch arm having a hook-shaped end adapted to engage said stud.

2. A latch comprising a pair of plates, one of said plates having a headed stud, a pair of washers pivotally supported from the other plate, a latch arm mounted between said washers and having a slot formed therein, a pivot pin carried by said last mentioned plate and passing through said washers and said latch arm, and a pin extending through said latch arm and entering said washers, said latch arm having a hook-shaped end adapted to engage said stud, said pivot pin

being headed, and a spring surrounding said pin and bearing against said head and the upper of said washers.

3. A latch comprising a pair of plates, one of said plates having a headed stud, a pair of washers pivotally supported from the other plate, a latch arm mounted between said washers and having a slot formed therein, a pivot pin carried by said last mentioned plate and passing through said washers and said latch arm, and a pin extending through said latch arm and entering said washers, said latch arm having a hook-shaped end adapted to engage said stud, and a pair of diametrically spaced ears projecting upwardly from said upper washer.

In testimony that we claim the foregoing we have hereunto set our hands at Milwaukee, in the county of Milwaukee and State of Wisconsin.

ORTON L. PRIME.
ALFRED LAUKHUFF.
